(57) **CLAIM**

The ornamental design for a personal monitoring device, as shown and described.

DESCRIPTION

FIG. 1 is a front elevational view of a personal monitoring device in accordance with the present invention;

FIG. 2 is a rear elevational view thereof;

FIG. 3 is a top elevational view thereof;

FIG. 4 is a bottom elevational view thereof;

FIG. 5 is a right side elevational view thereof;

FIG. 6 is a left side elevational view thereof;

FIG. 7 is a left side perspective view thereof;

FIG. 8 is a right side perspective view thereof;

FIG. 9 is a top perspective view thereof; and,

FIG. 10 is a bottom perspective view thereof.

More generally, the invention pertains to an ornamental design for an article of manufacture. In one embodiment, as indicated above, the article of manufacture is a personal monitoring device to be worn on a finger of the human body as a ring would be worn.
